CLAIM

The ornamental design for a cup holder assembly as shown and described.

DESCRIPTION

FIG. 1 is a perspective view of a cup holder assembly. FIG. 2 is a perspective view of the cup holder assembly, with the base shown separately for ease of illustration.

FIG. 3 is a side view of FIG. 2.

FIG. 4 is an alternate side view of FIG. 2, shown rotated 180-degrees in respect to FIG. 3.

FIG. 5 is an alternate side view of FIG. 2, shown rotated 90-degrees in respect to FIG. 3.

FIG. 6 is an alternate side view of FIG. 2, shown rotated 90-degrees in respect to FIG. 4.

FIG. 7 is a top view of FIG. 2; and,

FIG. 8 is a bottom view of FIG. 2.

The broken lines show environmental subject matter and form no part of the claimed design.

1 Claim, 3 Drawing Sheets
